REFLECTOR

John A. McKay, Coshocton, Ohio, assignor to
Jones Metal Products Company, West Lafay-
ette, Ohio, a corporation of Ohio

Application December 6, 1934, Serial No. 756,249

6 Claims. (Cl. 240—103)

This invention relates to a reflector for electric lamps primarily for out of door use. My reflector is adapted for mounting at the upper end of a standard and comprises not only the reflecting member itself, but the supporting means therefor which also carries a socket for positioning an electric lamp within the reflector. A characteristic of my reflector is that it has at its upper end a drum of reduced size, or monitor 5 top, as I prefer to designate it, with a lateral window in it, so that in addition to reflecting the light downwardly it may throw a beam laterally.

My reflector is especially well adapted for use 15 in filling stations having external pumps, the reflector being adapted to illuminate the pumps and adjacent region and also throwing light toward the accompanying building. The invention is illustrated in the drawings hereof and is hereinafter more fully explained and the novel features are summarized in the claims.

In the drawings, Fig. 1 is a sectional side elevation of one form of the reflector proper and its support in position on top of an upright tubular post; Fig. 2 is a horizontal section through the post looking upwardly at the reflector, as indicated by the line 2—2 on Fig. 1; Fig. 3 is a vertical section through the monitor top of the reflector of Fig. 1, as indicated by the line 3—3 on that figure; Fig. 4 is a detail in enlarged section of the connection between the supporting rods and the reflector proper; Fig. 5 is a fragmentary sectional side elevation of a reflector having a modified form of monitor top.

As shown in Figs. 1 and 2, A designates a suitable upright supporting post or standard. Attached to the upper end of this post is a fitting 10, carrying the socket 12 for the lamp B. The fitting is a tubular member adapted to extend over the upper end of the post to which it is clamped by a set screw 15, passing through a reduced collar-like portion 16 of the fitting. Internally, the fitting has a transverse web 17 with an opening 18 for the passage of the electric conductors b and screw-threaded openings for the reception of screws 19 holding the socket in place.

The reflector proper in either form comprises a flaring lower portion or skirt 20 and a cylindrical upper portion 21, closed at its upper end by a slightly curved crown portion 22. Below this monitor top the flaring portion preferably extends laterally while curving downwardly in dish-form for some distance as at 23 and then 50 extends downwardly in a more abrupt conical

shape 24 terminating at a beaded lower edge 25.

A suitable lateral opening 26 is formed in the vertical wall of the monitor top to provide a window, and preferably behind this opening is an arcuate transparent pane 30 of glass or similar material. This pane may be held in place by suitable clips 31 engaging the lower edge, and clips 32 and 33 engaging its end edges. When constructed as illustrated in Figs. 1 and 3, the bottom clips 31 and one of the end clips 32 are 10 permanently secured to the reflector while the other end clip 33 is removably held by screws or other means, thus enabling the pane to be readily mounted or replaced, as desired.

To hold the reflector described in proper position relative to the lamp B, I provide three rods 40, secured at their lower ends to the fitting 10 and at their upper ends to the lower portion 20 of the reflector. These rods have lower end portions 41 bent at an angle to the main body of 20 the rod, these lower portions extending through vertical openings in a projecting collar 42 of the fitting, the rods being held in position by set screws 43. At their outer ends each rod has secured to it, by welding or brazing, an externally threaded bushing 45. Embracing this bushing is an internally threaded sleeve 46, which also embraces the externally threaded inner end portion of a plug 47 which extends through an opening in the reflector wall and has an enlarged 30 head on the outer side thereof. This makes a very neat and effective means of connecting the reflector to the supporting rods. The necks of the plugs 47 are merely passed through openings in the reflector and then the sleeves, which have been screwed well onto the bushings 45, are unscrewed from those bushings and screwed onto the plug extensions so that the reflector becomes tightly clamped between the sleeve and head of the plug.

The adjustment permitted by the described method of clamping the reflector, and the adjustment permitted by the vertical portions of the supporting rods through the collar of the fitting, enable the reflector to be accurately positioned with reference to the fitting and thereafter rigidly held thereon.

It will be noticed that in the embodiment of Fig. 1, the reflector with its monitor top and transparent pane presents a continuous imperforate structure, thoroughly water-tight from top to bottom. However, if desired, I may make ventilation openings through the cylindrical surface of the monitor top. Such construction is shown in Fig. 5, where these ventilation open- 55

ings are shown at 50. In this case I prefer to surmount the monitor top with a protecting hood 51 in order to prevent passage of rain or snow into the ventilation openings. This hood 5 is of scoop-shape, having a downwardly curved crown sheet and a wall 52, which is U-shaped in horizontal cross-section; that is to say, for the most part this wall is cylindrical and concentric with the monitor top but adjacent the 10 window diverges to leave a flaring open space for the emission of the rays of light through the window.

The hood described may be readily supported by means attached to the center of the crown 15 of the monitor top. I have shown for this purpose a headed bolt 53, passing through the crown of the hood, then through an intermediate distance ring 54 between the hood and crown 22 of the monitor top, and finally receiving a nut 55 on the underside of the crown 22. Such construction holds the crown of the hood spaced from the crown of the monitor top with the wall of the hood spaced from the cylindrical wall of the monitor top, and thus provides 25 an effective space for ventilation, at the same time preventing access of rain or snow to the openings 50.

It will be noticed that with either embodiment 30 of my reflecting member, the monitor top with its crown and the flaring skirt of the reflector may be one integral member, for instance, of metal with enamel facing. The supporting fitting may be a single integral casting. All other parts of the construction are simple and readily 35 applied. My reflector therefore may be cheaply constructed; there is nothing about it to get out of order, and experience has demonstrated it is very efficient when installed.

I claim:

- 40 1. A reflector having a flaring skirt portion and a monitor top in the form of a cylindrical drum with a crown, ventilation openings and a light transmissive window through the cylindrical wall of such drum, and a hood over the monitor top having a crown portion and a depending skirt and spaced from the crown and cylindrical wall of the monitor top said hood flaring outwardly adjacent the window to permit the direct passage of light therefrom and yet protect the ventilation openings from the weather.

2. A reflector made of one continuous integral piece of metal and having a lower conical portion, a dish-shaped portion leading inwardly and upwardly from the conical portion, a round, concentric upward extension from the dish-shaped portion, and a top for said extension, the extension being provided with a lateral window, a translucent pane within the extension and extending across the window, and means on the interior of the extension for holding the pane 10 in place.

3. A reflector made of one continuous integral piece and having a lower conical portion, a dish-shaped portion leading inwardly from the conical portion, a round concentric upward extension from the dish-shaped portion having ventilation openings, and a top for said extension spaced a substantial distance from said extension to provide ventilation, said extension being provided with a lateral window and a light trans- 20 missive closing means for said window.

4. The combination of a reflecting member having a flaring skirt and a monitor top with a lateral window and ventilating openings, a pane of light-transmissive material covering 25 said window, means for supporting the reflecting member and for supporting an electric lamp in such position that some of the rays of the lamp pass directly through the window in the top and a hood to protect said window from 30 the weather, said hood being substantially spaced from monitor top to permit ventilation through said ventilating openings.

5. A reflector having a flaring skirt portion and a monitor top with ventilation openings 35 and a light-transmissive window in said top, and a hood over said top and flaring outwardly adjacent the window to permit direct passage of light therethrough and yet protect the ventilation opening from the weather.

6. A reflector shell, having ventilation openings and a light-transmissive window, a hood carried by said shell and substantially spaced therefrom to cover said ventilation openings and yet permit access thereto of air and said 45 hood flaring outwardly adjacent the window to permit direct passage of light therefrom and yet protect the ventilation openings from the weather.

JOHN A. MCKAY. 50
